J. Doolittle;
Charcoal Kiln.
Patented Dec. 14, 1829.

Isaac Stoddard, Brattleboro Vermont,

Seller's Patent.

The Schedule referred to in these Seller's Patent and making part of the same, containing a description in the words of the said Isaac Stoddard, himself of his improvement in the art of burning wood for the manufacture of charcoal.

To all persons to whom these presents shall come. Isaac Stoddard of Brattleboro, in the County of Bennington & State of Vermont, send greeting. Be it known that I the said Isaac Stoddard, have invented, constructed, made and applied to use a new & useful improvement in the art of burning wood for the manufacture of charcoal, specified in the words following, viz. This improvement consists in charring the wood in close & permanent kilns, instead of covering it in the usual way with stones, stones or other earth; Which kiln is built of brick, stones or other proper materials, laid in mortar, and may be either circular or square or of angular form, the upper being circular shape, in account of the greater facility of supporting the roof, as will be seen here after. Holes may be made of any size to hold from one to fifty or more cords of wood. The walls are built vertically to the height of four or twelve feet more or less as may be convenient, leaving a list of round holes at the bottom, & two or more rows of round holes between these & the top of the walls. When the side walls have attained the height to which it is intended to carry them, the top is reinforced with a strong band of iron, the ends of which should be strongly joined, by bolts or otherwise to prevent the spreading of the walls by the weight of the roof & the top or roof is arched over in the form of a dome, leaving one or more lists of round holes in the dome between the spring of the arch & the center & an opening of about one foot diameter in the center of the dome; the round openings in each tier or range should be at the distance of three to four feet from each other on the outside of the kiln, & about ten or twelve feet or under, & diminishing rising from the foot or base to near the top of the kiln to facilitate the working; The intermediate foot prints are exposed to view & left open or closed as may be

required; in the side walls are left one or more openings as sometimes
more demands in the form of doors, for or using with wood & dis-
charging coal. The bottom of the floor of the kiln is laid with its
outer edge on a level with the bottom of the foot of the kiln, & is slightly
raised towards the centre; this may be made of a floor of common
boards laid on sand & covered with three or four inches of clay
smoothly & compactly laid on or it may flagged with stones or
paved with bricks, or in any other manner which will render
it smooth & solid. The kiln may be filled with wood either
by setting the wood on end, as in the ordinary heat pit, or by
laying it down as in a cord heap, if the latter method which is
prefer, be adopted, it will be well to place some small pieces of
wood loosely over the bottom, for the body of wood to rest upon, in order
that the air may circulate freely under it. The smallest & driest
wood should be placed at the bottom of the kiln covering the
largest (& it is no matter how large) for the upper half a thin
lay of wood may be laid in the middle corresponding with
the opening in the centre of the dome; if so, some dry wood
beams should be placed in the centre at the bottom. When the
kiln is entirely filled with wood the chinking doors must be
closed, either with iron doors bolted, or by wooden work, & the fire
introduced thro' the central opening at the top; when the fire
is kindled this opening must also be closed, which may be done by
laying over it an iron plate & some earth; the fire can be easily
and effectually governed by opening or closing cuts as cir-
cumstances require; an experienced master may very soon learn
to discover & to know the state of the fire within from the nature
of the smoke from the mouth & draw the fire whichever way he chooses;
when the wood is sufficiently charred, the fire may be easily extinguished
by closing all the mouths and every fissure hermetically; & in a few days
it will be sufficiently cool to open & draw out the coal & substitute other
wood when the operation recommends. What I claim as new and
not the object of this application is the construction of permanent
kilns.

kilos above ground, with ached roofs, chimneys, & front holes as above described and for the purpose aforesaid, to a size sufficient to do business on an extensive scale. By the addition of a simple apparatus, this method of shaving wood may afford vast quantities of pyrolytic acid, which may be applied to a variety of uses in the arts.

In testimony that the above is a true specification of my said improvement as above described, I have hereunto set my hand & seal this sixteenth day of Nov. in the year of our Lord one thousand eight hundred & twenty nine. T. D.
